UNITED STATES PATENT OFFICE.

HAROLD JARVIS, OF BUFFALO, NEW YORK.

TYPE-WRITING MACHINE.

No. 819,998.

Specification of Letters Patent.

Patented May 8, 1906.

Application filed January 2, 1904. Serial No. 187,440.

To all whom it may concern:

Be it known that I, HAROLD JARVIS, a citizen of the United States, residing at Buffalo, in the county of Erie and State of New York, 5 have invented new and useful Improvements in Type-Writing Machines, of which the following is a specification.

This invention relates generally to type-writing machines in which the impression of the type upon the paper is effected automatically by power instead of by the physical force of the operator upon the keys, but more particularly to a machine of this character in which the type wheel or carrier and other power-driven parts are actuated by mechanical means.

The object of my invention is to construct an efficient machine of this class which can be operated with very little effort and at a practically unlimited speed.

In the accompanying drawings, consisting of three sheets, Figure 1 is a sectional elevation of my improved machine. Fig. 2 is a sectional elevation of the friction-clutch, 25 which connects the continuously-rotating driving and driven shafts and the slide for vibrating the type wheel or carrier, the slide being in its depressed position. Fig. 3 is a view similar to Fig. 2, showing said slide 30 locked in its elevated position to prevent double or repeated printing of the type-wheel for a single depression of a key. Fig. 4 is a horizontal section in line 4-4, Fig. 2. Figs. 5 and 6 are detached face views of the cams which 35 vibrate the type-wheel. Fig. 7 is a horizontal section of the machine in line 7-7, Fig. 1. Fig. 8 is a fragmentary horizontal section in line 8-8, Fig. 1, showing the carriage-feed mechanism. Fig. 9 is a cross-section in line 9-9, Fig. 1. Fig. 10 is a fragmentary side elevation of the shift-keys of the type-wheel and their stops. Fig. 11 is a rear elevation of the 40 upper portion of the machine, partly in section. Fig. 12 is an enlarged cross-section in line 12-12, Fig. 1.

Similar letters of reference indicate corresponding parts throughout the several views.

A indicates the horizontal base-frame of the machine, which may be of any suitable 50 construction, and A' is an elevated top plate or frame suitably supported on said base-frame and carrying the paper-carriage and other parts of the machine.

B is the main driving-shaft of the machine, 55 arranged vertically in the lower rear portion

thereof and continuously rotated in the use of the machine from any available source of power. I prefer to employ for this purpose an electric motor B' of any ordinary construction, in which case the shaft B carries the armature of the motor. Above this shaft and arranged in axial alinement therewith is a second or driven shaft C, which is journaled in a standard or bearing c, mounted on the top plate A', the shaft being held against vertical movement in its bearing by any suitable means. The upper shaft C is driven from the main shaft B by a clutch or connection which is so constructed as to transmit the motion of the main shaft to the shaft C under ordinary conditions, but permits the motion of the latter shaft to be arrested while the main shaft continues to rotate. The preferred transmitting device shown in the drawings, Figs. 1, 2, and 3, consists of a friction-clutch comprising a head d, rigidly secured to the driven shaft C and provided with depending spring-tongues d', the free lower ends of which embrace the edge of an annular head d², secured to the upper end of the driving-shaft B, the friction between this head and the spring-tongues being sufficient to compel the driven shaft C to turn with the driving-shaft B, except when the driven shaft is positively held from turning.

E is a type-wheel or revoluble type-carrier bearing one or more rows of characters on its periphery in a manner common to this class of type-writing machines and adapted to vibrate toward and from the usual platen F for imprinting its characters on the paper. This type-wheel is mounted on a shaft e, so as to turn therewith, and this shaft is connected with the upper end of the driven shaft C by a universal joint e' of any suitable construction, 95 which compels the type-wheel shaft to turn with said shaft and yet permits the type-wheel to swing freely toward and from the platen. The type-wheel shaft is journaled at its ends in an upright vibratory yoke or frame E', provided at its base with laterally-extending arms or trunnions e², which are journaled in standards e², rising from the top plate A', as shown in Fig. 11. The type-wheel is swung away from the platen by a spring e¹, resting upon a bracket e³ of one of the standards e² and bearing at its upper end against a shoulder of a rod e⁵, which latter is pivoted at its upper end to a forwardly-extending arm of the adjacent trunnion, as 110

shown in Figs. 1 and 11. The rod e^5 is guided in an opening in the bracket e^3 . The type-wheel, while compelled to turn with its shaft, is free to slide axially thereon for bringing 5 one or another of its rows of characters in the proper printing position. The connection between the type-wheel and its shaft (illustrated in the drawings) consists of a flanged sleeve g , secured to the type-wheel shaft and 10 provided with upwardly-projecting guide-pins g' , which pass loosely through openings formed in the bottom of the wheel and in a smooth disk or washer g^2 , interposed between the wheel and the flange of said sleeve, as 15 shown in Figs. 1 and 11. The type-wheel is yieldingly held in its depressed position, in which its upper row of small letters is presented to the platen, by a spring g^3 , which surrounds the type-wheel shaft between the top 20 of the wheel and the upper arm of the vibratory frame E' .

The continuously-rotating type-wheel is arrested at different predetermined points in its rotation preparatory to imprinting the desired characters by an annular series of movable stops h , which are individually projected by means of the key-levers I into the path of a radial stop-arm h' , rigidly connected with the driven shaft C , preferably by being secured to the fixed head d of said shaft, as 25 shown in Fig. 1. The stops h consist of vertical pins arranged in an annular row concentrically with the shaft C and sliding in guide-openings formed in a fixed horizontal ring H , 30 which is supported by standards h^2 , secured to the upper plate of the base-frame A . There are as many of these stop-pins as there are key-levers I , and the lower end of each pin is connected with the rear end of one of the key-levers, preferably by providing the flattened 35 lower ends of the pins with vertical slots and passing the hook-shaped rear ends of the key-levers loosely through said slots. The key-levers are fulcrumed between their ends upon 40 a common pivot-rod i , supported at its ends in bearings on the base-frame A , and the rear arms of the levers are guided in the slots of an upright comb i' , secured to the top of the base-frame. During the use of the machine 45 the stop-arm h' sweeps over the upper edge of the guide-ring H , and the stop-pins h are normally retracted out of the path of said arm by the weight of the inner arms of the key-levers, which arms are preferably longer 50 than their front arms to which the keys i^2 are secured, as shown. If desired, the stop-pins may be further held in their depressed position by springs i^3 , acting to depress a pair of vertically-swinging arms i^4 , pivoted to the 55 base-frame A and carrying a universal bar i^5 , Figs. 1 and 7. This bar extends across the upper sides of the key-levers behind the pivot-rod i , and thus tends constantly to depress the rear arms of said levers and the stop-pins. 60

65 Upon depressing a key-lever the companion

stop-pin h is raised into the path of the constantly-rotating stop-arm h' , as shown by dotted lines in Fig. 1, thereby arresting the arm, the driven shaft C , and the type-wheel connected therewith preparatory to the forward or printing stroke of the wheel. The various stop-pins h are so arranged that upon depressing the key representing the desired character the type-wheel will be stopped in its rotation the instant that its corresponding 75 character arrives opposite the printing-point.

It will now be understood that when no key is depressed the driven shaft C together with the stop-arm h' and the type-wheel are constantly rotated in the same direction at 80 a comparatively high speed, say about five hundred revolutions per minute, and that under these conditions no slippage takes place between the members $d' d^2$ of the friction-clutch. When, however, the driven shaft C 85 is arrested by the elevation of one of the stop-pins h , the lower clutch member d^2 , carried by the driving-shaft, slips on the spring-tongues d' until the depressed key is released and the raised stop-pin is retracted out of the path of 90 the stop-arm, when the friction-clutch again compels the driven shaft C to turn with the driving-shaft, the two shafts turning together until the stop-arm h' encounters another projected stop-pin, and so on as long as the keys 95 are operated.

The forward or printing stroke of the type-wheel is effected by the following mechanism: J is a vertically-movable rod sliding in an opening in the standard c and provided at its upper end with a rigid laterally-extending arm j . The upward movement of this arm is transmitted to the vibratory type-wheel frame E' , preferably by means of a comparatively stiff bow-spring j' , the upper end of which is secured to the lower corner of said frame, while its lower end rests loosely on the arm j . The rod J extends below the top plate A' and is adapted to be elevated by a vertically-reciprocating member or slide K , 100 composed of heads or disks k , having central openings for the passage of the shaft C , and vertical rods k' , connecting said disks on opposite sides of said shaft and passing loosely through openings in the fixed head d , as 105 shown in Figs. 1, 2, 3, and 4. On the opposing faces of the lower clutch-head d^2 and the lower disk of the slide K are secured spiral cams $k^2 k^3$, which bear against each other. Whenever the shaft C is arrested by its arm 110 h' encountering one of the stop-pins h , the continued rotation of the driving-shaft B causes the cam k^2 , connected therewith, to act upon and lift the cam k^3 , thereby elevating the slide K , which latter in turn lifts the 115 rod J , causing the type-wheel frame E' to be swung toward the platen through the medium of the arm j and the spring j' . As soon as the high end of the lower cam k^2 clears the 120 corresponding end of the upper cam k^3 the 125

slide K is depressed to its former position by a return - spring k^4 , which surrounds the driven shaft C between the fixed head d and the lower disk of the slide, and when this occurs the type-wheel frame is swung away from the platen by its return-spring. At the same time the rod J is lowered to its former position by the return movement of said frame. The purpose of the bow-spring C is to cause the type-wheel to strike the platen with an elastic or yielding blow and to avoid the necessity of accurately adjusting the position of the type-wheel frame relatively to the platen. Owing to the high speed of the driving-shaft B, the cams k^2 k^3 will repeatedly actuate the slide K, and consequently cause the type-wheel to make repeated impressions on the paper for a single depression of a key unless the key is quickly released. To obviate this objection in case the keys should be held down longer than is necessary to produce a single stroke of the type-wheel, I provide means for locking the slide K in its elevated position until the depressed key is released, thereby keeping the cam k^3 of the slide clear of the cam k^2 of the driving-shaft and preventing the cams from raising the slide more than once for a single depression of a key. The preferred device (illustrated in the drawings) consists of a horizontally-sliding bolt L, adapted to interlock with the upper disk of the slide K, as shown in Fig. 3. This bolt is guided in a pair of arms or hangers l, depending from a horizontal carriage L', which slides in guideways l', secured to the under side of the top plate A', as shown in Figs. 1, 3, and 9. A spring l², applied to this bolt between its head and the rear arm of its carriage, tends to keep the bolt in its normal forward position. (Shown in Fig. 1.) The bolt-carriage L' is reciprocated from the universal bar i⁵ by an upright elbow-lever L² fulcrumed on the base - frame A. When a key is depressed, the rear arm of the key-lever raises the universal bar i⁵, rocking the elbow-lever L² in the proper direction to shift the carriage L' rearwardly and move the spring-bolt L into the path of the upper head or disk of the vertically-movable slide K. This disk is beveled at its edge, as shown, and the head of the spring-bolt has a correspondingly-beveled nose over which the beveled edge of said disk rides freely during the upward movement of the slide K, allowing the disk to rise above the bolt, while the upper side of the bolt is abrupt, so as to check the descent of the slide until the bolt is withdrawn by the release of the depressed key. It will thus be seen that whenever a key is depressed, the bolt L is automatically thrust into the path of the slide and caused to lock the latter in its raised position, where its cam k^3 is out of reach of the cam k^2 of the driving-shaft. The cam of the driving-shaft can therefore act but once upon the cam of the

slide for a single depression of the key, thus avoiding repeated impressions of the corresponding character unless the operator releases and again depresses the same key. In some cases—for instance, in underscoring or 70 ruling—the capacity to make repeated impressions by the single depression of a key is a desirable feature, and in order to permit the operator to do this the stem of the locking-bolt L is extended forwardly within convenient 75 reach of the operator and provided with a ring or knob l³, whereby the operator may withdraw the bolt by hand for allowing the slide K to play freely up and down under the action of the cams k^2 k^3 , and thereby vibrate 80 the type-wheel so long as the key is held down.

The type-wheel shown in the drawings has three rows of characters, and in its normal lowermost position the upper row representing the small letters stands opposite the printing-point of the platen. The wheel is moved axially for printing characters in its intermediate and lower rows by a pair of shift-keys M M'. The levers m m' of these 85 keys are fulcrumed on the pivot-rod i, and the rear arm of the lever m acts upon the lower end of a lifting-rod m², having a laterally-extending arm m³, which bears against the smooth-bottom disk g² of the type-wheel, 90 so that upon depressing the shift-key M the type-wheel is raised in an obvious manner. The lifting-rod m² is guided in an upright bearing or standard M². Under the front arm of the key-lever m is arranged an adjustable stop m³, which is so adjusted as to limit the depression of said lever when the type-wheel is raised sufficiently to bring its lowermost row of characters into printing position. The lever m' of the other shift-key M' is provided at its rear end with a laterally-extending pin m⁴, which engages under the rear arm of the key-lever m, so that upon depressing the key M' it raises the type-wheel through the medium of the last-named key-lever. A 100 stop m⁵, similar to the stop m³, is arranged under the front arm of the key-lever m' and so adjusted as to limit the depression of the key M' when the type-wheel is raised to the proper height to bring its middle row of characters into printing position. 105

N indicates the paper-carriage, which runs upon transverse tracks n, mounted on the top plate A'. The carriage may be of any suitable construction, that shown in the drawings being provided with ball-bearings n' and retained upon its tracks by rollers n², journaled on the carriage and running against the outer flanges of the tracks. The usual spring-drum N' may be employed for advancing the carriage. Any suitable carriage feed or escapement mechanism may be employed. 110

The feed mechanism shown in the drawings is constructed as follows: o is a rack secured horizontally to the front side of the carriage 115

and having ratchet-teeth at its front edge. With these teeth engage a pair of detent-pawls o^5 o^6 , which are carried by a vertically-swinging lever o^3 , pivoted at o^4 to the standard c . Both of these pawls are pivoted to swing laterally in one direction under the action of springs o^5 o^6 , while their movement is limited in the opposite direction by suitable stops. The movement of the lever o^3 causes 5 the two pawls to engage the rack o alternately in a manner similar to the well-known escapement-pawls employed on the Remington and similar type-writing machines. The rear arm of the lever o^3 is provided with a laterally-extending tail o^7 , which overlaps the arm of the vertically-sliding rod J , whereby said lever is rocked simultaneously with the forward stroke of the type-wheel. The return stroke of the lever o^3 is effected by a spring o^8 . 10 P is the space-bar, secured to the front ends of a pair of levers p p' , fulcrumed on the pivot-rod i . One of these levers—say the right-hand one, p' —is provided at its rear end with a lateral pin p^2 , which extends beneath 15 one of the key-levers I , so that upon depressing the space-bar said key-lever is caused to project the corresponding stop-pin h into the path of the rotary stop-arm, thereby causing the rock-lever o^3 of the carriage-escapement 20 to be actuated through the medium of the cams k^2 k^3 , slide K , and rod J in the same manner as when a key is depressed and allowing the carriage to advance a step. As the impression-stroke of the type-wheel is also 25 effected by the upward movement of the actuating-rod J , it is necessary to provide means for disconnecting the type-wheel frame from this rod in order to prevent the wheel from delivering an impression simultaneously with 30 the depression of the space-bar. This is accomplished by making the arm j laterally movable relatively to the spring j' , so that when the arm is swung under the lower end of this spring the upward movement of the 35 arm is imparted to the type-wheel frame, while when the arm is withdrawn from under the spring the latter and the type-wheel frame are unaffected by the upward movement of said arm, and only the rock-lever o^3 of the 40 carriage-escapement takes part in that movement. The rod J is free to turn in its bearing, and its arm j is swung laterally by a transverse shipper-rod q , sliding in a standard q' and having upwardly-projecting pins which 45 embrace said arm, as shown in Figs. 1, 8, and 11. This shipper-rod is actuated from the left-hand lever p of the space-bar P by a bell-crank lever q^2 , one arm of which connects with the shipper-rod, while its other arm is 50 connected with said lever by a rod q^3 . In order to insure the engagement of the arm j with the spring j' , the arm is provided at its leading edge with a laterally-projecting beveled tip q^4 , as shown in Figs. 1, 8, and 12. The 55 tail of the rock-lever o^3 is arranged directly

over the pivot rod or axis J of the arm j , so that the lever always remains in engagement with said arm.

The operation of the machine is as follows: During the use of the machine the driving-shaft B runs constantly and the friction-clutch d' d^2 tends to drive the intermediate shaft C and the type-wheel continuously in the same direction, the stop-arm h' rotating idly with the driven shaft C when no keys are 70 depressed. When a key is depressed, the corresponding stop-pin h is raised into the path of the stop-arm h' , stopping the rotary type-wheel in the proper position to bring the corresponding letter or other character opposite the printing-point, and the instant after this occurs the type-wheel is swung toward the platen by the upward movement of the slide K and caused to imprint the character on the paper, as hereinbefore described. By 75 the depression of the key I the locking-bolt is thrust into the path of the slide K , and just before the slide reaches the end of its upward stroke its beveled upper edge trips over the beveled nose of said locking-bolt, which latter 80 then interlocks with the slide and retains the same in its raised position, preventing repeated vibrations of the type-wheel and of the escapement-lever o^3 for a single depression of the key. Upon releasing the key the 85 locking-bolt L is withdrawn, allowing the slide K to descend to its initial position and the type-wheel to be swung backward by the action of the return-springs k^4 and e^4 . At the same time the raised stop-pin h is retracted, 90 allowing the stop-arm h' and the shaft C to continue their rotary movement until said arm is again arrested by the depression of the same or another key. When it is desired to print a character appearing in one of the two 95 lower rows of the type-wheel, the appropriate shift-key M or M' is depressed just before operating the key representing the desired character, when the type-wheel will be shifted axially on its shaft to the proper printing-level 100 through the medium of the lifting-rod m^2 and arm m^3 , as hereinbefore described. During 105 all of the above operations the actuating-arm J remains in engagement with the spring j' of the type-wheel frame E' . When, however, the space-bar P is depressed, said actuating-arm is swung laterally clear of said spring, as shown by dotted lines in Fig. 8, allowing the type-wheel frame to remain at 110 rest and actuating only the escapement-lever o^3 . This action takes place whenever the space-bar is operated; but as soon as this bar is released the arm j is automatically swung under the spring j' ready to vibrate the type-wheel frame upon the depression of a writing-key. This return stroke of the arm j is effected by the spring-pressed universal bar i^5 115 acting upon the key-lever with which the space-bar lever p engages, as already explained. 120

As the type-wheel and the carriage-feed mechanism are actuated by power, the machine can be operated with ease, the mere weight of the fingers being sufficient to 5 press the keys, which require but a short stroke or depression to elevate the light stop-pins *h*, and as the shaft from which the type-wheel is driven is constantly clutched to the continuously-rotating driving-shaft the arrested type-wheel is instantly and quickly rotated the moment a depressed key is released, permitting the machine to be operated at a very high speed. The machine thus saves much time and labor and enables 15 the operator to perform an increased amount of work with less fatigue than by the use of an ordinary type-writing machine. In addition to these advantages the machine has the merit of being comparatively simple in construction, enabling it to be produced at small cost as compared with other power-driven type-writing machines.

I claim as my invention—

1. In a type-writing machine, the combination with a platen, of a continuously-rotating driving-shaft, a driven shaft, a friction-clutch constantly connecting said shafts, a type-carrier bodily movable toward and from the platen and rotated from said driven shaft, 25 stop mechanism for arresting said driven shaft at different points in the rotation of the type-wheel, and keys for controlling said stop mechanism, substantially as set forth.

2. In a type-writing machine, the combination of a continuously-rotating driving-shaft, 35 a driven shaft, means for transmitting motion from the driving to the driven shaft, a vibratory type-carrier rotated from said driven shaft and pivotally connected therewith, means for stopping said driven shaft at different points in the rotation of the type-carrier, and means for vibrating said carrier, substantially as set forth.

3. In a type-writing machine, the combination of a continuously-rotating driving-shaft, 45 a driven shaft, power-transmitting means for causing the driven shaft to rotate constantly with the driving-shaft except when arrested, a vibratory type-carrier connected with said driven shaft to turn therewith, means for stopping said driven shaft at different points in the rotation of the type-carrier, and vibrating means for the type-carrier actuated from said driving-shaft, substantially as set forth.

4. In a type-writing machine, the combination of a continuously-rotating driving-shaft, a vibratory frame movable relatively to said shaft, a rotary shaft journaled in said frame, 60 a type-carrier mounted on the last-named shaft, power-transmitting means for causing said type-carrier shaft to rotate constantly with said driving-shaft except when arrested, means for stopping the type-carrier shaft at 65 different points in the rotation of the type-

carrier, keys for controlling said stop mechanism, and means for vibrating said frame, substantially as set forth.

5. In a type-writing machine, the combination with a driven shaft having a stop-arm, a driving-shaft and a clutch connecting said shafts, of a vibratory frame, a type-carrier journaled in said frame and rotated by said driven shaft, movable stops adapted to project into the path of said stop-arm, keys for operating said stops, and mechanical means for vibrating said frame actuated from said driving-shaft, substantially as set forth. 75

6. In a type-writing machine, the combination with an operating-shaft, of a vibrating frame, a type-carrier shaft journaled at both ends in said frame and pivotally connected with said operating-shaft, a type-carrier mounted on the second-named shaft between the bearings thereof, and means for vibrating 85 said frame, substantially as set forth.

7. In a type-writing machine, the combination of a continuously-rotating driving-shaft, a driven shaft carrying a stop, a clutch connecting said shafts, a type-carrier rotated 90 from said driven shaft, a series of stops or abutments movable into and out of the path of said shaft-stop, means for actuating said abutments and a carriage carrying a platen arranged opposite the type-carrier, substantially as set forth. 95

8. In a type-writing machine, the combination of a continuously-rotating driving-shaft, a driven shaft carrying a radial stop-arm, a friction-clutch constantly connecting said shafts, a type-carrier rotated from said driven shaft, a series of stops or abutments surrounding the driven shaft and individually movable into and out of the path of said arm, and means for projecting and retracting 100 said abutments, substantially as set forth. 105

9. In a type-writing machine, the combination of a continuously-rotating driving-shaft, a driven shaft having a radial stop-arm, a friction-clutch constantly connecting said 110 shafts, a type-carrier rotated from said driven shaft, an annular row of stops or abutments arranged concentrically with the driven shaft and individually movable into and out of the path of said stop-arm, and keys for actuating 115 said abutments, substantially as set forth.

10. In a type-writing machine, the combination of a continuously-rotating driving-shaft, an upright driven shaft, a friction-clutch constantly connecting said shafts, a type-carrier rotated from the driven shaft, an annular frame surrounding said shaft, a stop-arm rotating with said driven shaft and arranged to sweep over said annular frame, upright stop-pins guided in said frame and adapted to be projected into the path of said stop-arm, and operating-keys connected with said stop-pins, substantially as set forth. 120 125

11. In a type-writing machine, the combination with a driving-shaft and a driven shaft, 130

- of a friction-clutch connecting said shafts and comprising a clutch member carried by one of said shafts and elastic members carried by the other shaft and bearing against said 5 clutch member, a type-carrier rotated from said driven shaft, and means for stopping the driven shaft at different points in the rotation of the type-carrier, substantially as set forth.
- 10 12. In a type-writing machine, the combination with a driving-shaft and a driven shaft, of a friction-clutch connecting said shafts and comprising an annular head secured to one of said shafts and a head secured 15 to the other shaft and carrying spring-tongues which are arranged lengthwise of the shaft and bear at their free ends against the periphery of said annular head, a type-carrier rotated from said driven shaft, and stop 20 mechanism for arresting said driven shaft at different points in the rotation of the type-carrier, substantially as set forth.
13. In a type-writing machine, the combination of a continuously-rotating driving-shaft, a driven shaft, means for transmitting 25 motion from the driving to the driven shaft, a vibratory frame, a type-wheel journaled in said frame and rotated from said driven shaft, an actuating member for said vibratory 30 frame movable lengthwise of said driven shaft, and means for operating said actuating member, substantially as set forth.
14. In a type-writing machine, the combination of a continuously-rotating driving-shaft, a driven shaft, means for transmitting 35 motion from the driving to the driven shaft, a vibratory frame, a type-wheel journaled in said frame and rotated from said driven shaft, an actuating-slide for said vibratory frame, 40 and coöperating cams mounted on said driving-shaft and said slide, substantially as set forth.
15. In a type-writing machine, the combination of a continuously-rotating driving-shaft, a driven shaft, means for transmitting 45 motion from the driving to the driven shaft, a vibratory frame, a type-wheel journaled in said frame and rotated from said driven shaft, an actuating-slide for said vibratory 50 frame, means for moving said slide in one direction, and a spring for moving the same in the opposite direction, substantially as set forth.
16. In a type-writing machine, the combination with a continuously-rotating driving-shaft and a driven shaft, of a friction-clutch 55 connecting said shafts and consisting of a head secured to the driving-shaft and a head secured to the driven shaft and having spring-tongues arranged lengthwise of said shafts and bearing against the first-named head, a vibratory type-carrier rotated from said driven shaft, a slide for vibrating the type-carrier guided on said driven shaft, coöperating 60 cams arranged on the slide and said annular clutch-head for shifting the slide in one direction, a spring for shifting said slide in the opposite direction, and means for stopping the driven shaft at different points in the rotation of the type-carrier, substantially as set forth. 70
17. In a type-writing machine, the combination with a shaft and a vibratory type-carrier rotated therefrom, of a sliding actuating-rod for vibrating the carrier arranged substantially parallel with said shaft, and means for operating said rod, substantially as set forth. 75
18. In a type-writing machine, the combination with a continuously-rotating driving-shaft, a driven shaft and a clutch connecting said shafts, of a vibratory type-carrier rotated from said driven shaft, means for stopping the driven shaft at different points in the rotation of the type-carrier, a sliding actuating-rod for vibrating the type-carrier arranged substantially parallel with the driven shaft, a slide acting upon said actuating-rod, and means for operating said slide, substantially as set forth. 80
19. In a type-writing machine, the combination with a continuously-rotating driving-shaft, a driven shaft and a clutch connecting said shafts, of a vibratory type-carrier rotated from said driven shaft, means for stopping the driven shaft at different points in the rotation of the type-carrier, a sliding actuating-rod for vibrating the type-carrier, a slide acting upon said rod, and coöperating cams for actuating said slide mounted on the driving-shaft and the slide, substantially as set forth. 95
20. The combination of a shaft, a vibratory frame carrying a type-wheel which is rotated from said shaft, an actuating member for said frame arranged to reciprocate lengthwise of said shaft, and a spring arranged to transmit motion from said actuating member to the type-wheel frame, substantially as set forth. 105
- 110
21. In a type-writing machine, the combination with a continuously-rotating shaft, a driven shaft and a clutch connecting said shafts, of a vibratory frame, a type-wheel having its shaft journaled in said frame, a universal joint connecting the type-wheel shaft with said driven shaft, stop mechanism for arresting said driven shaft at different points in the rotation of the type-wheel, and means for vibrating said frame, substantially as set forth. 115
22. In a type-writing machine, the combination with a continuously-rotating driving-shaft, a driven shaft and means for transmitting motion from the driving to the driven shaft, of a vibratory type-carrier rotated from said driven shaft, an actuating member for vibrating the type-carrier operated from the driving-shaft, a keyboard, and means controlled by the keys for preventing more than 120
- 125
- 130

one operation of said actuating member for each depression of a key, substantially as set forth.

23. In a type-writing machine, the combination with a continuously-rotating driving-shaft, a driven shaft and means for transmitting motion from the driving to the driven shaft, of a vibratory type-carrier rotated from said driven shaft, a reciprocating member for 10 vibrating the type-carrier operated from the driving-shaft, a keyboard, and locking mechanism controlled by the keys for temporarily holding said reciprocating member out of engagement with the driving-shaft, substantially as set forth.

24. In a type-writing machine, the combination with a continuously-rotating driving-shaft, a driven shaft and means for transmitting motion from the driving to the driven shaft, of a vibratory type-carrier rotated from said driven shaft, a reciprocating member for vibrating the type-carrier, actuating means for said member operated by the driving-shaft, a keyboard, a bolt or catch adapted to interlock with said reciprocating member, and actuating means for said bolt controlled by the keys, substantially as set forth.

25. In a type-writing machine, the combination with a continuously-rotating driving-shaft, a driven shaft and means for transmitting motion from the driving to the driven shaft, of a vibratory type-carrier rotated from said driven shaft, a reciprocating member for vibrating the type-carrier, actuating means for said member operated by the driving-shaft, a keyboard, a universal bar operated by the keys, and a bolt or catch controlled by said universal bar and adapted to interlock with said reciprocating member, substantially as set forth.

26. In a type-writing machine, the combination with a continuously-rotating driving-shaft, a driven shaft and means for transmitting motion from the driving to the driven shaft, of a vibratory type-carrier rotated from said driven shaft, a reciprocating member for vibrating the type-carrier having a beveled face, a spring-bolt arranged to interlock with said member and having a beveled 50 nose adapted to be engaged by the corresponding face of the reciprocating member during the effective stroke of the latter, a keyboard, and a carriage for said spring-bolt controlled by the keys, substantially as set forth.

27. In a type-writing machine, the combination with a continuously-rotating driving-shaft, a driven shaft and means for transmitting motion from the driving to the driven shaft, of a vibratory type-carrier rotated from said driven shaft, a reciprocating member for vibrating the type-carrier having a beveled face, a spring-bolt arranged to interlock with said member and having a beveled 65 nose adapted to be engaged by the corre-

sponding face of the reciprocating member during the effective stroke of the latter, a carriage for said spring-bolt, a keyboard, a universal bar operated by the keys, and an elbow-lever connecting said carriage with the 70 universal bar, substantially as set forth.

28. In a type-writing machine, the combination with a continuously-rotating driving-shaft, a driven shaft and means for transmitting motion from the driving to the driven shaft, of a vibratory type-carrier rotated from said driven shaft, a reciprocating member for vibrating the type-carrier operated from the driving-shaft, a keyboard, locking mechanism controlled by the keys for temporarily holding said reciprocating member out of engagement with the driving-shaft, and a manual releasing device for said locking mechanism, substantially as set forth.

29. The combination with a vibratory type-wheel frame, a paper-carriage and a feed device for the carriage, of a common actuating mechanism for the type-wheel frame and said feed device, a space bar or key, and means controlled by the space-bar for disconnecting the type-wheel frame from said actuating mechanism, substantially as set forth.

30. The combination with a vibratory type-wheel frame, a paper-carriage and a feed device for the carriage, of a driving-shaft, a 95 common actuating mechanism for the type-wheel frame and said feed device operated from the driving-shaft, a space bar or key, and means controlled by the space bar for disconnecting the type-wheel frame from said actuating mechanism, substantially as set forth.

31. The combination with a vibratory type-wheel frame, a paper-carriage and a feed device for the carriage, of a driving-shaft, a common actuating member for the type-wheel frame and said feed device operated from said shaft and capable of a reciprocating movement for actuating both said parts and a lateral movement for clearing the type-wheel frame, and a space bar or key operatively connected with said actuating member, substantially as set forth.

32. The combination with a vibratory type-wheel frame, a paper-carriage and feed device for the carriage, of a driving-shaft, a 115 common actuating-arm for the type-wheel frame and said feed device capable of a reciprocating movement for actuating both of said parts and a swinging movement for clearing the type-wheel frame, a slide for reciprocating said arm, co-operating cams carried by said slide and the driving-shaft, and a space bar or key operatively connected with said actuating-arm, substantially as set forth.

33. The combination with a vibratory type-wheel frame, a paper-carriage and feed device for the carriage, of a driving-shaft, a common actuating-arm for the type-wheel frame and said feed device capable of a reciprocating movement for actuating both of said 130

- parts and a swinging movement for clearing the type-wheel frame, a slide for reciprocating said arm, actuating means for said slide operated by said driving-shaft, a shipper-bar connected with said actuating-arm, and a space bar or key operatively connected with said shipper-bar, substantially as set forth.
34. The combination with a vibratory type-wheel frame provided at its lower end with a spring, a paper-carriage and a feed device for the carriage, of a driving-shaft, an actuating-arm for said feed device and said type-wheel frame bearing against the lower end of said spring and capable of a combined reciprocating and lateral movement, means for reciprocating said arm actuated from the driving-shaft, and a space bar or key for swinging said arm out of engagement with said spring, substantially as set forth.
35. The combination with a continuously-rotating driving-shaft, a driven shaft and a clutch connecting said shafts, of a vibratory frame, a type-wheel having its shaft journaled in said frame and rotated from said driven shaft, a paper-carriage, a feed device for the carriage including a pawl-lever, a sliding rod provided with an arm which engages said lever, a spring interposed between said arm and said vibratory frame, and actuating mechanism for said rod operated from said driving-shaft, substantially as set forth.
36. The combination with a continuously-

rotating driving-shaft, a driven shaft and a clutch connecting said shafts, of a vibratory frame, a type-wheel having its shaft journaled in said frame and rotated from said driven shaft, a paper-carriage, a feed device for the carriage, a sliding rod arranged to actuate both said feed device and said vibratory frame, a reciprocating member acting upon said rod, and guided on said driven shaft, and coöperating cams mounted on said slide and said driving-shaft, substantially as set forth.

37. The combination with a continuously-rotating driving-shaft, a driven shaft and a clutch connecting said shafts, of a vibratory frame, a type-wheel having its shaft journaled in said frame and rotated from said driven shaft, a paper-carriage, a feed device for the carriage including a pawl-lever, a sliding rod provided with an arm which engages said lever, a spring interposed between said arm and said vibratory frame, and actuating mechanism for said rod operated from said driving-shaft, substantially as set forth.

Witness my hand this 30th day of December, 1903.

HAROLD JARVIS.
